UNITED STATES PATENT OFFICE

1,941,766

PNEUMATIC WATER SYSTEM

George L. Thom, Chicago, Ill., assignor to Chicago Pump Company, Chicago, Ill., a corporation of Illinois

Application June 23, 1932. Serial No. 618,898

18 Claims. (Cl. 103—6)

This invention relates to pneumatic water systems, and more particularly to water systems employing air pumps for supplying air under pressure to the storage tank of the system.

5 One of the objects of this invention is to provide an air pump actuated by the inflowing water which replenishes the water drawn from the storage tank.

Another object is to provide an air pump 10 actuated by the inflowing water with means to regulate the quantity of air fed during each cycle of operation, so that an excess of air will not be injected into the storage tank.

Other objects and advantages will appear in 15 the following specification, and with all of said objects and advantages in view, this invention consists in a pneumatic water system having an air pump operated by the inflowing water for supplying air under pressure to the storage tank. 20 It further consists in a system having a water pump for pumping water into a tank or other vessel and a fluid pump for injecting air or other fluids into the tank or vessel and operated by the inflowing water handled by the water pump. 25 The invention further consists in the several novel features hereinafter fully set forth and claimed.

The invention is clearly illustrated in the accompanying drawings in which:

30 Fig. 1 is a perspective view of a pneumatic water system equipped with an air injecting device included in the piping;

Fig. 2 is a central, vertical, longitudinal section through the air injecting device showing the 35 pistons at the top of their up stroke;

Fig. 3 is a detail, horizontal section taken on the line 3—3 of Fig. 2;

Fig. 4 is a detail, horizontal section taken on the line 4—4 of Fig. 2;

40 Fig. 5 is a central, vertical, longitudinal section of the air injecting device seen in Fig. 2, but showing the pistons thereof in an intermediate position;

Fig. 6 is a view similar to Fig. 5 of a modified 45 form of the air injector;

Fig. 7 is a perspective view of another modified form of the invention;

Fig. 8 is a detail, longitudinal section of the 50 air pump seen in Fig. 7 showing the two valve cylinders placed one above the other, and

Fig. 9 is a cross-section taken on the line 9—9 of Fig. 8.

Referring to said drawings, and first to Figures 55 1 to 5 inclusive, the reference character 10 designates a liquid pump, desirably an electrically op-

erated water pump which may be connected to the city main or to any other source of liquid supply, as by piping 11, and from the water pump piping 12 leads through a rubber hose or other vibration absorbing fitting 13, and through a 60 nipple 14 to a fluid injecting device here shown in the form of an air pump 15.

From the air pump, the piping continues through a nipple 16, a union 17 and a valve 18 to a pneumatic water tank or other liquid container, 19.

The storage tank is provided with a water glass 20, so that visual indications may be had of the water line to determine whether or not, more or less air need be added to the air cushion within 70 the tank. A branch pipe 21 connects with a visual pressure gauge 22 and a pressure switch 23, which is included in the electric circuit governing the intermittent operation of the electrically driven water pump 10, the electric wiring for which is 75 seen at 10°. This motive power is shown as one means, but it is to be understood that any equivalent means may be used such as steam driven equipment with its controlling means.

The storage tank 19 receives a quantity of water 80 from the water pump 10, where it is stored until demand is made by the building in which it is placed, and then the water flows from the storage tank through valve 24 and piping 25, which leads to the fixtures (not shown) in the building 85 which the system serves. A quantity of compressed air is confined in the upper part of the storage tank to give flexibility to the system, so that the water pump will not be required to operate every time a faucet is opened, but instead, 90 the water pump will handle a considerable quantity of water at each operation to serve the building for some time.

The air pump 15 comprises a relatively large water cylinder 26 (see Figs. 2 to 5 inclusive) and 95 a smaller air cylinder 27 with the cross-sectional areas varied so as to create a pressure differential. An outer casing 15^a of the cylinders 26, 27 has piping connections formed thereon by which the air pump unit is included in the piping system. 100

Leading down from the upper end of the air cylinder 27 to the piping 16 is a passage 41 which is controlled by a check valve 39, seating on a seat 40 at the top of the air cylinder. A valve controlled port 37 opens to the air cylinder at its top 105 through which air or other fluid is drawn into the air cylinder. An inwardly opening check valve 36 controls the port 37. The water cylinder 26 is open at both ends and communicates at its upper end with the chamber 15^b of the casing 15^a, which 110

also communicates with the air cylinder 27 through ports, slots or openings 38 adjacent the lower end of the air cylinder. The lower open end of the water cylinder 26 communicates with the piping 16 through a duct 31 and a restricted orifice 32. Desirably, the cylinders 26, 27 are provided with linings 29, 35 as shown.

Sliding within the water cylinder 26 is a piston 28 and connected to said piston as by a stem 10 33 is an air piston 34, which slides in the air cylinder 27. Fig. 2 shows the pistons 28, 34 at the upper limit of their up stroke which is the position occupied when the water pump is at rest, the pistons being held in this position by the higher pressure on the under side of the larger piston 28.

Flow of water through the casing is indicated by the arrows *a* (Fig. 2) and when the water pump starts operation, pressure builds up in the supply line to the unit 15, and this higher pressure exerts a downward force on the piston 28 to slide it down through the cylinder 26 until this piston engages a lug 30 on the casing.

With the higher pressure forcing the piston 28 down, the water within the casing below said piston has to be forced out or displaced, through the duct 31 and orifice 32 to the piping 16, which leads to the storage tank 19. This regulated flow gives the piston 28 a timed movement to minimize shock, and also to improve the operation of the unit during its cycle. The piston 28 may be of the type shown, built up of leather cups separated by spacers and followers or it may be of metal construction throughout with piston rings as in common practice.

35 When the piston 28 is forced down, the air piston 34 tends to rarify the air within the cylinder 27, at which time free air at atmospheric pressure forces past the check valve 36 into the cylinder 27 and fills the cavity therein. This presents a chamber of free air at substantially atmospheric pressure.

Continued downward movement of the piston 28 draws the air piston 34 down past the intermediate position seen in Fig. 5 to a position indicated 45 by the dotted lines in Fig. 2, where it exposes the slots or ports 38 to permit the water under pressure from the piping 14 chamber 15 and the water cylinder 27 to pass through the ports 38 and up through the cylinder 27 where it forces the free air (previously admitted to the cylinder 27) past the check valve 39 and then through the passage 41 and the piping 16 to the storage tank.

Immediately following the entrapped air, the water handled by the water pump flows this 55 course on its way to the storage tank. Operation of the water pump 10 continues until sufficient pressure is built up in the storage tank to actuate the pressure switch 23 to open the circuit through the pump motor. Then as the water pump comes 60 to rest, the pressure on the water pump side of the air pump 15 falls below that on the storage tank side thereof. The check valve 39 seats to prevent a return flow through the air cylinder 27, but a small stream of water under pressure 65 from the storage tank passes through the orifice 32, through the duct 31 to the water cylinder 26 below the piston 28, and thereby raises the piston to its uppermost position, or until it contacts with the lower end of the wall of the cylinder 27 or an adjustable collar 42 thereon, which regulates the limit of upward travel of this piston. With the rise of the piston 28, the air piston 34 also rises to force the column of water 70 above it past the check valve 39 or past the leather

cup of the piston 34 back into the low pressure space.

When sufficient water has been withdrawn from the storage tank 19, the confined pressure again falls so as to actuate the pressure switch 23 and again operate the water pump. With each cycle of operation, the air pump 15 performs a complete cycle of operation and injects a certain volume of air into the storage tank to replace air which may have been absorbed by the water or which may have escaped through small leaks.

As the volume of air is limited in the smaller systems, a balance will be reached to maintain a fairly uniform condition of operation. When the system is first started, the water pump will raise the water level quite high in the storage tank due to the smaller quantity of confined air within the tank. This means that at each cycle of operation the water pump under this condition will operate during shorter intervals and put less water during each operation into the storage tank, resulting in more operations to supply a given quantity of water. This will cause a greater quantity of air being forced into the 100 storage tank, and as the system gets further along in this service, this condition works more toward a normal operation.

From this sub-normal condition at the start, the air injected will be greater than needed, and 105 as the quantity of confined air increases, the water level will drop until such a time when the air injected will balance the loss due to absorption or leak losses, and the water pump will then have fewer cycles of operation with greater 110 quantities of water furnished during each operation.

In Fig. 6, substantially the same elements are used to accomplish the desired end as in the form illustrated in Figs. 1 to 5. In this case, the position of the parts are reversed, the water cylinder 46 being located above the air cylinder 54. The lining 48 of the water cylinder 46 is provided with ports 49 opening to a cavity 50 in the casing and controlled by a ring like flexible valve 55 to prevent inflow into the water cylinder 46 from the cavity 50. The nipple 14 is attached to a fitting on the casing 44 and the flow of water is through the chamber 45 to the upper end of the water cylinder 46. Pressure from the higher pump side 120 forces the piston 47 down through the water cylinder 46 until the piston passes the row of ports 49, at which time the flow is through these ports to the cavity 50, and thence through the nipple 16 to the storage tank.

A stem 51 carries an air piston 52 which slides in the air cylinder 54. In the downward movement of the air piston 52 water which has previously accumulated in the air cylinder 54 is squeezed past the leather cup of the air piston, 135 thence up through the air cylinder 54 and out through the upper end thereof into the cavity 50 and out through the piping to the storage tank.

When the water pump stops, the differential pressures on the two connections to the air pump 140 again reverses. This causes the higher tank pressure to press the leather or similar valve 55 to seat against the ports 49 to thereby restrict reversal of flow through these ports. However, this higher pressure in this reverse direction does 145 not exert itself on the piston 47 and forces it upwardly to the top of its stroke or until it contacts an adjustable stop here shown as comprising a screw 56 which may be hydraulically sealed in the casing by a pliable gasket 57 and a lock nut 150

58. This upward movement lifts the air piston 52 which causes air at atmospheric pressure to pass by the air check valve 59 and fill the cavity in the cylinder 54 formed by the rising air piston. 5 The air piston rises sufficiently high to open the ports formed by slots 60 formed in the walls of the air cylinder. This liberates the air from the air cylinder through these ports and allows 10 water to flow into the air cylinder to displace entrapped air. The air thus liberated is collected in the cavity 50 and upon the next operation it is carried on to the storage tank.

Every time the water pump operates, it builds up a higher pressure in the piping towards the 15 storage tank and when the water pump stops, a reverse condition exists. By this pressure reversal, the air pump is actuated by first one stroke and then a return stroke, and during each 20 complete cycle of operation a volume of air is injected into the storage tank, taking it in at atmospheric pressure and releasing it within the air pump casing at the lower pressure present. The air pump uses only the flow of the water in 25 the system from the water pump to the storage tank to effect its operation.

The modification shown in Figs. 7, 8 and 9 provides for larger installations where the storage tank capacities may be rated for one thousand gallons of water or more. This system comprises 30 basically the same elements above described, but the modification includes a well known standardized adaptation of water or lift pump having a double acting piston. In this modified form, a city service pipe 61 leads preferably through a 35 valve 62 and T 63 to an electrically driven water pump 64. From the water pump, the piping 61^a includes a T 65, a union 66, a check valve 67 and a gate valve 68 on the way to the storage tank 69. The building service piping from the storage 40 tank leads through a valve 71 and the piping 72 to the fixtures (not shown) in the building. The tank is likewise provided with a water glass 73 and fittings and is also provided with a pressure switch 73^a to control the operations of the pump 45 motor.

A reduced pipe line 74 leads from the T 65 through a controlling valve 75 to a hydraulically operated air pump 76 of conventional form and the water discharged from this pump is through 50 piping 77 and preferably back to the T 63 in the service pipe 61. In this assembly, a small portion of the water handled by the water pump bypasses through the air pump 76 and is recirculated through this source as long as the water 55 pump operates and the valve 75 is open.

The hydraulically operated air pump 76 is preferably double acting and during a normal period of operation of the water pump 64, the air pump makes a number of strokes to inject 60 numerous quantities of air into the storage tank 69 to meet the demands. As the quantity of confined air within the storage tank increases, the controlling valve 75 may be partly closed, or as the case may be, this valve may be entirely closed 65 until more air is needed.

Although the exact construction of the hydraulically operated air pump 76 is not material to this invention broadly considered, I shall describe the one shown in detail. The hydraulically operated air pump 76 shown comprises a water cylinder 78 (see Figs. 8 and 9) in which two spaced pistons 79 are slidably mounted. These pistons are spaced by a stem 80 which extends into an air cylinder 81 through packings 82 and carries an air piston 83 in the air cylinder.

As the water pistons 79 reciprocate, the air piston 83 successively causes air to enter the air cylinder 81 at atmospheric pressure through air check valves 84, and then forces the entrapped air through check valves 85 and through the piping 86, check valve 87 and valve 88 to the storage tank 69. 80

In Fig. 8, which is merely a schematic view of the two valve cylinders 95, 99 which contain the valves 89, 96 they are positioned one above the other for the purposes of illustration, but it is to be understood that they are located side by side as is seen in Fig. 9. The ports are indicated diagrammatically by parallel lines. 85

The water pistons 79 are actuated by water 90 controlled by a main water valve 89 through ports 90, 91 and a discharge port 92. This main valve 89 is built up of a number of pistons 93 spaced on a stem 94 and slidably mounted in a cylinder 95. The spacing of these pistons forms a number of 95 zones which function to connect or cut off water passages as will be explained hereinafter. An auxiliary valve 96 controls the operation of the main valve 89. This auxiliary valve 96 also comprises a built up construction of pistons 97 held 100 in spaced relation on a stem 98 and slidably mounted in the cylinder 99.

Water under pressure from the water pump 64 enters the cylinder 99 from the piping 74 between the innermost pistons 97. Assuming the valves 105 and pistons in the position shown in Fig. 8, water passes from the central zone of the cylinder 99 through port 100 to one end of the cylinder 95 to force the valve 89 to the position shown. This allows inflowing water to pass from cylinder 99 110 through port 101 into cylinder 95 between two of the end pistons 93 and from this chamber through the port 90 to force the pump pistons 79 to position shown. This exposes a port 102 115 and allows water under pressure to flow back to the cylinder 99 beyond one end of the valve 96 to slide this valve to the limit of its opposite travel. As this valve 96 is moved, water from the corresponding space at its opposite end is discharged 120 through a port 103 to the low pressure discharge port and out through the piping 77.

When the valve 96 has changed its position, reverse action is set up in the valve 89. The water which previously operated this valve will 125 be discharged through port 100 which will then be communicating through the space between the associated end pistons with port 104 which in turn leads to the discharge port 92. The high pressure flow is then from the cylinder 99 through 130 the port 105 to cylinder 95 to slide the valve 89 to its limit of movement in the opposite direction. This allows water under pressure to flow through port 106 and then through the port 91 to move the pump pistons 79. This action repeats itself 135 as long as water under pressure flows from the piping 74 to the piping 77 and the number of operations determines the quantity of air injected into the storage tank.

Other modifications are apparent from the 140 above specification and it is obvious that instead of injecting air into a storage tank, chemicals may be injected into the liquids being pumped such as chlorine gas injected into water for 145 swimming pools, boiler compounds in make up water for steam boilers and precipitating any sewage which is being pumped. It is to be understood that the element 69 referred to as a storage tank may comprise a steam boiler into which 150

chemicals may be introduced by the air injecting device.

I claim as new and desire to secure by Letters Patent:

5. 1. In a system of the class described, in combination, a liquid container, a centrifugal liquid pump supplying liquid to said container and a fluid injecting device for injecting fluid into said container, said fluid injecting device having a pipe connection with the liquid pump and being actuated by pressure set up by said liquid pump. 80
10. 2. In a system of the class described, in combination, a storage tank, a controlled intermittently operated centrifugal water pump supplying water to said storage tank, and an air pump for injecting air into said storage tank, said air pump having a pipe connection with water pump and being actuated by pressure set up by said water pump. 85
15. 3. In a system of the class described, in combination, a storage tank, an intermittently operated centrifugal water pump for supplying water to said storage tank under pressure, controlled means for the motive power of the water pump responsive to changes of conditions taking place in the storage tank, and a fluid injecting device for injecting fluid into said storage tank, said fluid injecting device having a pipe connection with the water pump and being actuated by pressure set up by the water pump. 90
20. 4. In a system of the class described, in combination, a storage tank, a controlled intermittently operated centrifugal water pump supplying water to said storage tank, and an air pump for supplying air to the storage tank, said air pump having pipe connections with the water pump and with the storage tank and, being actuated by the water pumped from said water pump to said storage tank. 95
25. 5. In a system of the class described, in combination, a storage tank, a controlled intermittently operated centrifugal water pump supplying water to said storage tank, and an air pump for injecting air into said storage tank, said air pump having a pipe connection with the water pump and being actuated by the pressure set up between said water pump and said storage tank. 100
30. 6. In a system of the class described, in combination, a storage tank, a controlled intermittently operated centrifugal water pump, piping between said water pump and storage tank, and a fluid injecting device for injecting fluid into said storage tank interposed in said piping, said fluid injecting device being actuated by pressure set up by said water pump. 105
35. 7. In a system of the class described, in combination, a storage tank, a controlled intermittently operated centrifugal water pump, piping between said water pump and storage tank, and an air pump for injecting air into said tank interposed in said piping, said air pump being actuated by pressure set up by said water pump. 110
40. 8. In a system of the class described, the combination, a storage tank, a controlled intermittently operated water pump, a water discharge pipe between said water pump and tank, a hydraulically actuated air pump for injecting air into said storage tank and piping from said water discharge pipe to said air pump. 115
45. 9. In a system of the class described, in combination, a storage tank, a controlled intermittently operated water pump, piping between said water pump and tank, a hydraulically actuated air pump for injecting air into said storage tank, 120
50. 10. said air pump having an air discharge pipe connected to the tank, and water inlet and water discharge sides, piping connections between the discharge side of the water pump and water inlet side of the air pump and piping connections between the water discharge side of the air pump and inlet pipe to the water pump. 125
55. 11. In a system of the class described, in combination, a storage tank, a controlled intermittently operated centrifugal water pump having piping connections with the storage tank, and through which the water is conducted to the tank, and a hydraulically actuated piston air pump having piping connections with the storage tank and adapted to inject air into the same, said air pump having piping connections with the discharge side of the water pump. 130
60. 12. A tank for containing a usable quantity of liquid held in confined limits, a centrifugal liquid pump for supplying additional liquid to said usable quantity, a pipe connection between said liquid pump and the tank for conveying the liquid to the tank, and a liquid operated fluid pump for adding a foreign fluid to said liquid, said liquid operated fluid pump being interposed in said pipe connection and being actuated by the liquid supply from said liquid pump. 135
65. 13. In a unit of the class described, a liquid actuated fluid pump comprising differential pistons and cylinders in which said pistons slide, one of said cylinders serving to handle liquid and another fluid, and one of said pistons being actuated by a source of liquid supply under pressure, and the other of said pistons being actuated by said first mentioned piston for injecting said other fluid into the liquid actuating said first mentioned piston. 140
70. 14. In a unit of the class described, a liquid actuated fluid pump comprising differential pistons and cylinders in which said pistons travel, one of said cylinders serving to handle liquid and another fluid, and one of said pistons being actuated upon by liquid in its travel through the fluid pump and the other of said pistons injecting said other fluid into said liquid during the operation of said air pump. 145
75. 15. In a unit of the class described, a liquid actuated fluid pump comprising differential pistons and cylinders in which said pistons travel, a liquid inlet chamber communicating with said cylinders through ports in the wall of the smaller cylinder, there being a valve controlled inlet port leading to said smaller cylinder and a valve controlled discharge passage leading from said smaller cylinder, and there being a duct leading from said discharge passage to the larger cylinder. 150
80. 16. In a unit of the class described, a liquid actuated fluid pump comprising differential pistons, and cylinders in which they travel, a liquid inlet chamber communicating with the larger of said cylinders, and a discharge passage connecting with the smaller cylinder, through ports in the wall of the smaller cylinder, there being a valve controlled air inlet port leading to said smaller cylinder, and valve controlled discharge ports leading from said larger cylinder to said discharge passage, and said pistons controlling the ports in the two cylinders. 155
85. 17. In a unit of the class described, in combination, a pair of differential pistons, cylinders in which said pistons travel, an air check valve opening to the smaller cylinder, a water inlet chamber leading to the larger cylinder and a water and air discharge passage leading from the smaller cylinder, there being a valve controlled port 160

leading from the larger cylinder to said discharge passage and controlled by the larger piston and there being a port leading from the smaller cylinder to said discharge passage controlled by the 5 smaller piston.

17. The combination of a container for liquid, a centrifugal liquid pump for supplying liquid to the container and a fluid pump for supplying a fluid to said container, said fluid pump having 10 connections with the liquid pump and having pump mechanism continually driven by liquid pumped by said liquid pump.

18. The combination of a container for liquid, a liquid pump for supplying liquid to the container and a fluid pump for supplying a fluid to said container, said fluid pump having connections with the liquid pump and having also 80 a hydraulically operated piston reciprocated by liquid pumped by said liquid pump and valve mechanism for controlling the reciprocations of the piston.
